METHOD OF FORMING A PRINTING PLATE

Valentin Dietz, Boedigheim, Badischer Odenwald, Germany, assignor to Dilith Corporation, Societe Anonyme, Luxembourg, Luxembourg, a corporation of Luxembourg

No Drawing. Filed Jan. 28, 1954, Ser. No. 406,876

1 Claim. (Cl. 101—149.2)

The present invention relates to a new and improved process for forming a printing plate for intaglio and flat printing.

It is one object of this invention to provide a new and improved surface and intaglio printing process which can be carried out in a simple and effective manner, and which produces long runs of clear prints with sharply defined contours.

Other objects of this invention and advantageous features thereof will become apparent as the description proceeds.

According to the process of this invention the carrier or support of the image, design, or lettering to be printed is provided with a tannable or hardenable, image-receptive gelatin layer the thickness of which in the swollen state must not exceed about 0.1 mm. Such an extremely thin colloidal layer is first subjected to preliminary tanning or hardening treatment in such a manner that the image, design, or lettering subsequently applied to said pre-tanned or pre-hardenable colloidal layer is also subjected to a certain degree of preliminary tanning or hardening. Said preliminary tanning or hardening treatment renders the colloidal layer extremely stable and durable so that it does no longer dissolve even when exposed to the action of boiling water. Provision of such an extremely thin colloidal layer prevents too deep a final image-fixing tanning or hardening and, consequently, too deep an impression of the image, design, or lettering to be printed and, thus, produces especially sharp prints.

Extensive experiments have shown that exposure to light which, heretofore, was considered as being essential, can be eliminated and replaced by incorporating into the pre-tanned or pre-hardenable, very thin colloidal layer compounds which change the image, design, or lettering produced on the colloidal layer, by chemical reaction.

For this purpose, chromic acid or its salts are added to the writing, drawing, or image-forming agent, such as typewriter ribbon, ink or the like. On the other hand, small amounts of a reducing agent capable of reducing chromic acid, such as, for instance, hydroxylamine hydrochloride, monomethyl p-amino phenol sulfate or the like, are added to the pre-tanned or pre-hardenable, very thin tannable or hardenable colloidal layer. On drawing or writing on said layer, chromic acid present in the drawing, writing, or image-forming agent encounters the reducing agent present in said layer and is reduced, even in the absence of actinic light, at the marked areas, thereby forming chromic chromate or other chromium salts of lower degree of oxidation. The course of said reduction reaction is revealed by a brownish discoloration of the originally yellow image, design, or lettering. Said reduction reaction proceeds, even in the dark, much quicker than the reaction caused by exposing the layer to light. It is advisable to apply the reducing agent only after the image, design, or lettering has been drawn or written on said colloidal carrier and after any required corrections have been made.

To carry out the process according to the present in-

vention, the image, design, or lettering to be printed is directly drawn or written on the pre-tanned or pre-hardenable, very thin colloidal layer by means of a bichromate containing writing, drawing, or image-forming agent, 5 when said printing surface is used in offset printing. Or the image, design, or lettering to be printed is first drawn or written on a piece of paper by means of a bichromate containing writing, or drawing, or other image-forming agent and said original is then transferred to the moistened and slightly dried pre-tanned or pre-hardenable, very thin colloidal layer to form thereon an image, design or lettering in reverse, in case said colloidal printing surface is used in direct printing. In both cases, the entire image, design, or lettering is coated with a solution, for instance,

15 of
4 g. of hydrazine hydrochloride,
20 g. of hydroquinone,
2 g. of sodium hydroxide,
55 cc. of water, and
20 924 cc. of alcohol.

Said solution, almost instantaneously, causes tanning or hardening of the image, design, or lettering.

Such a final tanning or hardening due to the action 25 of the reducing agent is new and of utmost importance since it renders the printing process independent from a source of light and since it can be carried out with considerably greater speed. This is of great advantage for the layman using this method of reproduction in his 30 office.

Printing surfaces according to the present invention are far superior to other known printing surfaces in that they tenaciously retain the greasy image-forming material, that they will not tone-up during use, that the 35 images, designs, or lettering produced thereon will not fall off during use, that they will withstand considerably more pressure without distortion than heretofore produced images, designs, or lettering, that said surfaces will permit erasure without the use of liquids and without 40 showing the erasure, that they have a remarkably long service life, that they will produce prints of extraordinary sharpness and definition, even in long runs, and that they have other greatly improved characteristics.

The term "tanning" as used herein and in the claims 45 annexed hereto, refers to a treatment of the water soluble colloidal layer whereby its water solubility is reduced and it is hardened.

The preliminary tanning or hardening treatment is preferably effected by means of formaldehyde. Care must 50 be taken not to cause too strong a tanning or hardening of the colloidal layer because, in this case, the colloidal layer will accept the printing ink not only at those places where the image, design, or lettering has been produced by subsequent tanning or hardening of said colloidal layer 55 but also at those other places exposed to such excessive preliminary hardening. The colloidal layer must also not be too soft because then it is not suitable for the production of sufficiently long runs due to a disintegration of the colloidal layer on printing.

60 Subsequent tanning or hardening to fix the image, design, or lettering to the colloidal layer requires a degree of tanning or hardening which prevents the image, design, or lettering from dissolving and disintegrating in the course of the normal printing procedure.

65 In general, as explained hereinbefore, two ways of producing the image, design, or lettering on the prehardened colloidal layer have proved to yield the desired results:

(a) The pre-tanned or pre-hardenable, very thin colloidal layer does not contain a reducing agent. The image-forming agent, for instance, the typewriter ribbon contains potassium bichromate. Writing with said bi-

chromate containing ribbon on the colloidal layer produces thereon the image. Final image-fixing tanning or hardening of the colloidal layer at those places where the image to be printed has been written on is effected when moistening the colloidal layer and the image thereon with a reducing agent, such as hydroxylamine hydrochloride.

(b) According to another embodiment of this invention, as explained above, the pre-hardened colloidal layer is first moistened with a solution of said reducing agent. When writing on such a layer with a typewriter ribbon containing potassium bichromate therein, tanning or hardening of the image sets in instantaneously. Heretofore, such instantaneous production of an image, design, or lettering on a colloidal layer for subsequent printing was not possible. The most preferred agents for producing a printable image, design, or lettering on a pre-hardened colloidal layer are alkali bichromates and hydroxylamine salts although other agents, as explained hereinbefore, may also be used.

I claim:

In a method of forming a printing plate for flat and intaglio printing, the steps comprising placing a gelatin layer on a supporting backing, partially hardening said layer by treating with a tanning agent, printing on said layer with an image forming agent, containing a compound selected from the group consisting of chromic acid

5

and salts thereof, coating said printed layer with an agent capable of reducing said image forming agent, the reducing agent being selected from the group consisting of hydroxyl amine salts and monomethyl p-aminophenol sulfate, whereby the portions of said printed layer contacted by said image forming agent are hardened and caused to shrink.
